UNITED STATES PATENT OFFICE.

HARRY ERICH VOLKMAR BRÜCKNER, OF CHARLOTTENBURG, NEAR BERLIN, GERMANY, ASSIGNOR TO FIRM PARNOX AKTIENGESELLSCHAFT, OF LUCERNE, SWITZERLAND.

FUSE PLUG.

Application filed April 13, 1923. Serial No. 631,753.

To all whom it may concern:

Be it known that I, HARRY ERICH VOLKMAR BRÜCKNER, a citizen of Germany, residing at Charlottenburg, near Berlin, Germany, Philippstr. 6, have invented certain new and useful Improvements in a Fuse Plug, of which the following is a specification.

This invention relates to fuse plugs, and more specifically to Edison fuse plugs provided with a fuse support or carrier on which are mounted a plurality of fuses which can be successively brought into the circuit.

One object of the present invention consists in that the fuse support or carrier comprising the fuse wires is formed as a pin plug which may be inserted in the lower or foot part bearing the Edison screw, as an ordinary two- or three-pin plug is inserted in a wall-socket. For placing a fresh fuse wire in circuit it is merely necessary to pull the fuse carrier or pin plug out of the foot part, then to turn said plug for an angle which corresponds with the distance between two fuse wires arranged therein and to reinser the same in the lower part or foot. So the electric connection between the foot and the fuse carrier or plug here is produced in exactly the same manner as with an ordinary wall plug merely by the contact of the metal pin of the one part with the corresponding sunk contact of the other part. The electric connection therefore is the simplest possible and at the same time the surest possible and beats in both these respects the electric connection of the elastic sliding contacts which are commonly used with multiple fuse plugs.

The improved fuse plug further presents the advantage of great simplicity as it consists only of two separate parts and the upper part or fuse carrier may in the simplest possible manner be replaced by a fresh one if all the fuse wires have been used up, no screw or other elements having to be loosened for this purpose.

Two embodiments of the invention are shown by way of example in the accompanying drawing.

Fig. 1 shows the side elevation of a fuse plug according to the invention, partly in longitudinal section.

Fig. 2 is a plan view of the same.

Fig. 3 is a section on line A—B of Fig. 1. 55

Fig. 4 is a section on line C—D of Fig. 1.

Fig. 5 shows a slightly modified form of construction of the pin plug which forms the upper part of the device.

Fig. 6 is a section corresponding to that 60 of Fig. 4, but showing a somewhat modified form of the journal part.

Fig. 7 also is a section corresponding to that of Fig. 4 but showing a modification 65 of the foot part.

The foot part A of insulating material which has the usual metallic Edison screw B forming the one contact bears on its lower surface the other contact C. From this contact C the conductor D extends upward 70 through a central bore of the foot part A. The upper end of the conductor D is formed by a contact F arranged at a deeply hollowed out place of the upper face of part A. The contact F is arranged, as shown in the 75 drawing, in such a manner that it is well protected and cannot be readily touched by the hand or by a finger when the fuse carrier is being removed.

From the upper end of the metal coating 80 of the Edison screw B a wire or conductor G extends through a bore of the foot part A to a cavity in the top end thereof constructed like a plug sleeve for a pin plug.

The upper part of fuse carrier H of the 85 device is formed like a pin plug and comprises a series of parallel vertical bores J and K belonging together by pairs and arranged in two concentric circles (see Fig. 3). The bores J, K of each pair are connected the one with the other at their upper ends by transverse bores or grooves L. In each pair of bores J, K a fuse wire M (silver wire for instance) is inserted which extends through bore J and passes through 95 transverse bore or groove L into bore K.

The lower ends of all fuse wires M at the lower openings of the bores K are in contact with a brass plate N fixed upon the central part of the lower surface of the body 100 H. At this point the body H has the shape of a journal O or O' respectively, fitting into the corresponding cavity in the central part of the upper surface of the foot part A. This journal O may be either cylindrical (Fig. 4) or of prismatic shape (Fig. 6), the cavity designed to receive this journal being evidently of similar cross section.

The number of sides of the prism has to correspond with the number of fuse wires contained in the fuse carrier.

The other end of the fuse wire M lying in the bore J is connected with a plug pin E which projects downward from the fuse carrier H. This metal plug pin E fits into the upper end of the bore of the foot part A which contains the conductor G and is 10 constructed like a plug sleeve.

The upper part or fuse carrier H made from porcelain or similar insulating material is covered by a disk P of tinned sheet-iron, arranged above a mica plate Q which also 15 covers the grooves L for the fuse wires M. The tinned sheet-iron disk P has at the points above the ends of the bores J peep holes R (Fig. 2) which permit to simultaneously observe all the fuse wires. These 20 peep holes can be oblong instead of being circular as shown so that the entire grooves L with the parts of the fuse wires situated in the same will be visible.

When the device is to be employed, the 25 fuse carrier H is inserted into the foot part A of the fuse plug in such a manner that one of the contact pins E engages with the bore which contains the conductor G and comes in contact with this conductor directly or 30 with the metal coating of the plug sleeve connected therewith. Corresponding cavities W in the upper surface of part A are provided for the reception of the other pins, these cavities being however not connected 35 with conductors. A single circular groove X may also be arranged instead of said cavities in the surface of part A for the reception of the unused pins E as shown in Fig. 7. The brass plate N of the fuse carrier H comes at the same time in contact 40 with the contact plate F of the central conductor D of the foot part A as the pin E engages the bore containing conductor G. If the foot part A is then screwed into the 45 corresponding socket the fuse plug is ready for use.

If a fuse wire has fused owing to short-circuit it is merely necessary to pull out the fuse carrier H, to turn the same for an angle which corresponds to the distance between two contact pins E, and then to reinsert the same into the foot part, whereupon the device is again ready for use. By corresponding marks on the edge of the part H the required measure of the said turning thereof may be indicated. If the journal O' is of prismatic shape as indicated in Fig. 6 the angle for which the fuse carrier has to be rotated before reinserting it in 50 the foot part is also determined as the number of sides of the prism corresponds with the number and position of the fuse wires contained in the fuse carrier.

Instead of providing in the ends of the 55 bores J of the fuse carrier H a number of

pins E corresponding to the number of fuse wires, the lower ends of the bores J may be constructed so that they form pin-sleeves S (Fig. 5). In this case only one metal pin is required which must be fixed on the foot 70 part A above the conductor G and in current-conducting connection therewith. In this case as well as in the above described other case the pins E are preferably elastic in a similar manner as the pins of the commonly used pin plugs for wall sockets. 75

Any number of fuse wires M may be used, for instance 6, 12 or any other number, within the limit of the available space.

Having now particularly described and 80 ascertained the nature of my said invention, I declare that what I claim is:—

1. A fuse plug comprising a foot part having two contacts for engaging the connection-contacts of the lines one of which forming an Edison screw, and a freely removable fuse carrier containing a plurality of fuse wires with a common central fuse wire contact arranged on a centrally projecting journal of said fuse carrier and 90 fitting into a corresponding contact bore of the foot part, metal pins forming the second and separate contacts of one of said fuse plug parts, the corresponding second contacts of the other part consisting of sockets, 95 said metal pins engaging said sockets when the fuse plug is in use.

2. A fuse plug comprising a foot part having two contacts for engaging the connection-contacts of the lines in a receptacle 100 and a fuse carrier movable with regard to the foot part and containing a plurality of fuse wires, a common central contact for all fuse wires on the fuse carrier, a journal centrally projecting on the lower face of said 105 fuse carrier, said central contact being arranged on said journal, a central bore in said foot part, the common foot contact of said foot part ending within said bore, said journal fitting into said bore for engaging 110 said central contact of said fuse carrier with said foot contact, metal pins forming the second contact of one of said fuse plug parts, the corresponding second contacts of the other part ending within holes, said metal 115 pins engaging said holes when the fuse plug is in use.

3. A fuse plug comprising a foot part having two contacts for engaging the connection-contacts of the lines in a receptacle and 120 a fuse carrier movable with regard to the foot part and containing a plurality of fuse wires, a common central contact for all fuse wires on the fuse carrier, a journal centrally projecting on the lower face of said fuse 125 carrier, said central contact being arranged on said journal, a central bore in said foot part, the common foot contact of said foot part ending within said bore, said journal fitting into said bore for engaging said cen- 130

tral contact of said fuse carrier with said foot contact, metal pins projecting in circular arrangement on the lower face of said fuse carrier, each of said metal pins being in contact with one of said fuse wires, an Edison screw on said foot part, a conductor coming from the metal shell of said Edison screw and terminating in a hole in the upper face of said foot part, every one of said metal pins of said fuse carrier fitting in said contact hole.

4. A fuse plug comprising a foot part having two contacts for engaging the connection-contacts of the lines in a receptacle and a fuse carrier movable with regard to the foot part and containing a plurality of fuse wires, a common central contact for all fuse wires on the fuse carrier, a prismatic

journal centrally projecting on the lower face of said fuse carrier, said central contact being arranged on said prismatic journal, a prismatic central bore in said foot part, the common foot contact of said foot part ending within said prismatic bore, said prismatic journal fitting into said bore for engaging said central contact of said fuse carrier with said foot contact, metal pins forming the second contact of one of said fuse plug parts, the corresponding second contacts of the other part ending within holes, said metal pins engaging said holes when the fuse plug is in use.

In testimony whereof I have hereunto set my hand.

HARRY ERICH VOLKMAR BRÜCKNER.
